UNITED STATES PATENT OFFICE

2,088,009

ADJUSTABLE DATING STAMP

Louis Melind, Chicago, Ill.

Application June 25, 1934, Serial No. 732,222

23 Claims. (Cl. 101—111)

This invention relates to stamping devices, and is more particularly concerned with an adjustable dating stamp.

Stamps of the kind to which this invention pertains are commonly employed for stamping the date of reception or transmission of letters, papers, and the like. Briefly, the stamp of the present invention comprises a casing having the stamping assembly fixed to one end thereof. A handle is provided on the other end of the stamp casing, and a dating assembly of the four band type is disposed within the casing, this dating assembly having its lower end projecting through a slot formed in the stamping assembly and with the printing characters on the bands of the dating assembly disposed in the plane of the printing characters on the stamping assembly, for co-operation therewith.

Broadly, one of the main objects of the present invention is to provide a new and improved construction of stamp in which the stamping assembly may readily be detached from the stamp casing and another stamping assembly, having different printing characters thereon, substituted therefor.

Another object of the invention is to provide a new and improved construction of stamp in which the dating assembly may be adjusted with respect to the slot in the stamping assembly, so as to bring the printing characters on the bands of the dating assembly into the plane of the printing characters on any stamping assembly which may be secured to the stamp casing.

More specifically, the objects of the present invention reside in the provision of means of simple construction for detachably securing the stamping assembly to the casing, and the provision of means of simple construction for adjustably supporting the dating assembly within the casing.

Other objects and advantages of the invention will appear from the following detailed description when taken in connection with the accompanying drawing, in which:

Figure 1 is a front elevational view of a stamp embodying the principles of the present invention;

Figure 2 is a vertical sectional view of the stamp shown in Figure 1;

Figure 3 is a vertical sectional view, taken along the lines 3—3 of Figure 2;

Figure 4 is a fragmentary perspective view of a portion of the dating assembly adjusting means;

Figure 5 is a bottom plan view of the stamping assembly;

Figure 6 is a top plan view of the stamping assembly;

Figure 7 is a front elevational view of the stamping assembly; and

Figures 8 and 9 are a top plan and a vertical sectional view, respectively, of a new and improved form of band wheel for the dating assembly.

Referring now in detail to the drawing, the stamp of the present invention includes a casing 10, which is of generally rectangular form and may be formed of brass, or any other suitable material. This casing is open at both ends, and forms, in effect, a shell which is adapted for the reception of a dating assembly, designated generally at 11.

The dating assembly comprises an inverted U-shaped frame 12, the downwardly depending arms 13 of which are preferably reduced in width, as shown at 14. The frame may be formed of any suitable material, and each of the arms 13 thereof are notched at 15 to provide for the reception of a metal bar 16. This metal bar 16 has a snug fit in notches 15 and forms a bed plate for the dating bands 17. These dating bands are preferably formed of rubberized fabric, or any other suitable material, and are preferably four in number, although a greater or less number of bands may be employed without departing from the spirit of the present invention. These bands have small 30 rubber printing characters secured thereto, the printing characters on one of the bands being in the form of abbreviations of the several months of the year. Two of the bands carry cardinal numbers, by which the various combinations of the 35 days of the month may be obtained, and the other band contains printing characters forming the successive years as, for example, from 1934 to 1939, together with any other printing characters desired. These bands are endless 40 bands and are disposed between the arms 13 of frame 12. At their lower ends, the bands pass over the metal bar 16, and at their upper ends they pass over hubs 18, which are rigidly secured to operating wheels 19. These operating wheels 45 are relatively large compared to the hubs 18 and have their outer periphery serrated, as indicated at 20, to provide a gripping surface which may readily be grasped by the fingers to rotate the wheels. The wheels are each rotatably mounted 50 upon a shaft 21, this shaft being secured at its opposite ends in the arms 13, substantially centrally thereof. The bands are stretched tightly between the bar 16 and the hubs 18 of operating wheels 19 and have a friction fit with the hubs 18, 55

so that upon operation of the wheels 19 the bands will be caused to pass around the bar 16. The dating assembly is preferably inserted in the casing through the open upper end thereof, the casing being provided with a plurality of slots 22 through which the operating wheels 19 project outwardly of the casing. These slots extend downwardly from the upper edge of the casing and are of sufficient length to permit of the wheels moving vertically therein upon vertical movement of the dating assembly within the casing.

The dating assembly is adjustably mounted for vertical movement within casing 10 by means which will now be described. This adjustable mounting means comprises two flat metal plates 23, one of which is disposed along each of the longitudinal sides of the transverse portion 24 of the frame 12. Each of these plates is provided with two slots 25 which extend inwardly from the opposite shorter sides of the plates and adjacent the lower edge thereof. The longitudinal sides of the transverse portion 24 of frame 12 are notched inwardly from the outer edge thereof, as indicated at 26, to provide lugs 27, one of which is disposed at each of the four corners of transverse portion 24. The plates 23 fit in the notched portions 26 of transverse portion 24, and the lugs 27 extend into the slots 25 formed in plates 23. These lugs have a relatively snug fit in slots 25 and serve to secure the plates to frame 12. The depth of the notch 26 is approximately equal to the thickness of plates 23, so that the plates will lie in the plane of the sides of arms 13 of frame 12. It will also be noted that the portion 23 of the plates 23, below the slots 25, have their extreme outer ends cut away so that such portions will be disposed within the plane of the sides of arms 13.

Disposed between the two plates 23 is a solid block 29, which may be formed of brass, or any other suitable material. The opposite ends of this block are cut away to provide an outwardly extending inclined boss 30 on each side thereof. These bosses extend into and have sliding movement in inclined slots 31 formed in plates 23, these slots 31 extending substantially the full length of the plates. Substantially centrally thereof, the block is provided with a horizontally disposed opening 32 which is internally threaded to cooperate with external threads formed on the bolt or screw 33. It will be noted that the threads on bolt 33 terminate a short distance below the head 34 thereof, as indicated at 35. Also, at its outer end, the bolt extends for a short distance beyond the threaded portion thereof and is reduced in diameter, as indicated at 36. The reduced portion 36 of bolt 33 is journaled in an opening 37 in side wall 38 of the casing 10, and the portion 35 of bolt 33 is journaled in an opening 39 formed in the side wall 40 of casing 10. A washer 41 is disposed about the reduced portion 36 of bolt 33 and between the inner surface of side wall 38 and the threads 35 on the bolt. Likewise, a washer 42 embraces portion 35 of the bolt and is disposed between the threads thereof and side wall 40 of casing 10. These washers serve to prevent endwise movement of the bolt with respect to the casing.

To mount the dating assembly within casing 10, the plates 23 are first secured to frame 12 of the dating assembly. The metal block 29 is then disposed between the plates and its pair of bosses 30 engaged in the slots 31 formed in plates 23. This entire assembly is then inserted

into the casing through the open upper end thereof and is slid downwardly therein until the opening 32 in block 29 is in line with the openings 37 and 39 in the side walls 38 and 40, respectively, of the casing. The bolt 33 is then projected through opening 39 in the casing and threaded into opening 32 in block 29, after which washer 41 is placed on the reduced portion 36 of bolt 33 and such reduced portion then journaled in opening 37 of the casing. The washer 42 is preferably a split washer and may now be snapped over portion 35 of the bolt.

From the foregoing it will be apparent that as the bolt 33 is journaled in the openings 37 and 39 of the casing, the block 29, therefore, when threaded in either direction along the bolt, will be forced to move in a straight line across the casing. Clockwise rotation of bolt 33 will move block 29 toward the right hand side of the casing, as viewed in Figure 2, and counterclockwise rotation of the bolt will move the block toward the left hand side of the casing. Due to this straight line movement of block 29 across the casing, the inclined bosses 30, carried by the block, will set up a camming action therebetween and the lower edge of slots 31 in plates 23, in which they engage, thereby moving the plates 23, together with the dating assembly, downwardly within the casing when the block is moved to the right. When the block is moved to the left, a camming action will be set up between the upper edges of bosses 30 and the upper edges of slots 31, thereby raising the plates 23 and the dating assembly with respect to the casing. It will be apparent, therefore, that by properly rotating bolt 33 the dating assembly may be raised or lowered with respect to the casing. The block 29 contacting the left-hand side of the casing limits the upward movement of the dating assembly within the casing, while the contact of the block with the right hand side of the casing limits the downward movement of the dating assembly within the casing.

At its open upper end, casing 10 is closed by cover 43, the sides of which preferably extend down to and terminate closely adjacent the operating wheels 19, when such wheels, together with the dating assembly, are in their fully raised position within the casing. Screws 44, which extend through the sides 45 of the cover and thread into the casing, serve to secure the cover to the casing. A handle 46, preferably formed of wood, or any other suitable material, is secured to cover 43 by means of a screw 47. This screw threads into handle 46 and is rigidly secured at 48 to the cover 43, substantially centrally thereof, in any suitable or preferred manner. An opening 49 in the side of the cover 43 permits the insertion of an instrument to operate bolt 33.

At its lower end, the casing 10 has a stamping assembly, designated generally by the reference character 50, detachably secured thereto. This stamping assembly comprises an inverted cup-shaped member 51, which is of generally rectangular form and of sufficient size to project for a short distance beyond the walls of the casing. The cup-shaped member may be formed of brass, or any other suitable material, and is adapted for the reception of a pad 52. This pad may be formed of rubber, or any other suitable resilient material, and is suitably secured within cup member 51 by means of an adhesive, or in any other suitable or preferred manner. This pad forms a cushioning element for the printing characters 53 which are also secured to pad 52 by a suit-

able adhesive, or in any other suitable or preferred manner. In the form shown in the drawing, these printing characters comprise the words "Paid" and "John R. Doe Co.", although any other suitable characters desired may be employed. A slot 54 formed in cup member 51 and cushioning element or pad 52 permits the lower portion of the dating assembly to project therethrough so that the printing characters carried by the dating assembly may cooperate with the printing characters carried by the cushioning element. As the slot 54 is of sufficient size to permit the lower end of the dating assembly to be projected therethrough, it will be apparent that upon rotation of bolt 33, the dating assembly may be projected into or withdrawn from slot 54. This permits the dating assembly to be adjusted so that the printing characters carried thereby can be brought into the plane of the printing characters on any stamping assembly which is secured to the casing.

Stamping assembly 50 is detachably secured to casing 10 by means of two flat downwardly depending arms 55, which may be formed of any suitable metal. One of these arms is secured, at its upper end, to the inner surface of side wall 56 of the casing, and the other arm is secured, at its upper end, to the rear surface of wall 57 of the casing. These arms may be secured to the casing as by soldering, or in any other suitable or preferred manner. The arms lie closely adjacent the walls of the casing and terminate adjacent the open lower end thereof. At their lower ends the arms are flared outwardly, as shown at 58, and these outwardly flared portions of the arms are provided with a hook portion 59. This hook portion 59 is adapted to engage attaching members 60 secured to cup member 51.

The attaching members 60 are preferably formed of relatively stiff wire and are of generally U-shaped formation. There are two of these members, one disposed on each side of slot 54 and extending parallel thereto. The members are adapted to extend into casing 10 and are so located upon cup member 51 that when they are inserted into the casing they will contact the inner surface of walls 56 and 57 thereof. The arms 61 of members 60 are rigidly secured to cup member 51 and the transverse portion thereof is depressed, as indicated at 62, to form cam surfaces 63. These cam surfaces are adapted to engage the hook portions 59 of arms 55 and to force the lower ends of the arms inwardly of the casing to permit the depressed portions 62 of the attaching members to pass therebetween. After passage of the depressed portions, the arms will snap back toward the walls of the casing and the hook portions 59 will engage the depressed portions 62 to secure the stamping assembly to the casing. To remove the stamping assembly from the casing, the arms 55 are each provided with a button 65, which is secured to the arms and extends outwardly through an opening in the casing. By pressing inwardly on these buttons, the arms 55 will be forced inwardly of the casing, thereby removing hook portions 59 from beneath depressed portions 62 of members 60, and the stamping assembly may then be removed. It will be noted that plates 23 have been provided with a slot 66, into which the upper ends of arms 55 may extend upon downward movement of the dating assembly.

Figures 8 and 9 show a new and improved form of operating wheel for the dating bands. This wheel comprises a disc 68, the outer periphery of

which is serrated at 69 to provide a gripping surface to facilitate rotation of the wheel. Disc 68 is preferably formed of metal and is provided with a plurality of openings 70, each of which is partially countersunk from one side of the disc, as indicated at 71. These openings are connected by an arcuate groove 70', the depth of the groove being substantially the same as the depth of countersunk portion 71 of openings 70. Hub 72 of the wheel is preferably formed of rubber and 10 has a central bore 73 for mounting the wheel upon a shaft. Hub 72 is disposed on the side of the disc opposite the openings 70 and the arcuate groove 70', and the hub is secured to the disc by molding the rubber into the openings 70 and into 15 the groove 70'.

While preferred embodiments of the invention have been illustrated and described, by way of example, it will be obvious that changes may be made therein within the spirit and scope of the 20 invention and, therefore, the invention is not to be limited to the forms herein disclosed, except insofar as it may be so limited in the appended claims.

What I claim is:

1. A stamp of the class described, comprising a casing, a dating assembly disposed in said casing and movable upwardly and downwardly relatively thereto in a plane, a rotatable member, and means operatively associated with said rotatable member and said dating assembly for moving said dating assembly relatively to said casing, said member being journaled in said casing and having its axis disposed in angular relationship with respect to the path of movement of said 35 dating assembly, whereby any force exerted upon said member during a stamping operation will be in a plane disposed in angular relation to the axis of said member.

2. A stamp of the class described, comprising 40 a casing open at its upper end and a cover for closing said open upper end of said casing, a stamping assembly having a slot therein associated with said casing, a dating assembly disposed within said casing, and means associated 45 with said dating assembly and said casing and disposed wholly below said cover for moving the dating assembly relatively to the slot in said stamping assembly.

3. In a stamp of the class described, a casing, a 50 dating assembly comprising a frame disposed in said casing for vertical movement with respect thereto, a plurality of plates secured to said frame, and means carried by said plates and associated with said casing for imparting the vertical movement to said dating assembly.

4. In a stamp of the class described, a casing, a 55 dating assembly comprising a frame disposed in said casing for vertical movement with respect thereto, a plurality of plates having inclined slots 60 formed therein secured to said frame, and means engaging in the slots of said plates and associated with said casing for imparting the vertical movement to said dating assembly.

5. In a stamp of the class described, a casing, 65 a dating assembly comprising a U-shaped frame disposed in said casing, a plate disposed on each of the opposite sides of the transverse portion of said U-shaped frame, a block disposed between and carried by said plates, and means associated 70 with said block and said casing for moving said dating assembly relatively to said casing.

6. In a stamp of the class described, a casing, a 75 dating assembly comprising a U-shaped frame disposed in said casing, a plate disposed on each

- of the opposite sides of the transverse portion of said U-shaped frame, each of said plates having a slot formed therein, a block disposed between said plates, bosses on said block engaging in the slots in said plates, and means associated with said block and with said casing for moving said dating assembly relatively to said casing.
7. In a stamp of the class described, a casing, a dating assembly comprising a U-shaped frame disposed in said casing, a plate disposed on each of the opposite sides of the transverse portion of said U-shaped frame, each of said plates having slots formed therein, a block disposed between said plates, bosses on said block engaging in the slots in said plates, and a threaded bolt associated with said block and said casing for moving said dating assembly relatively to said casing.
8. In a stamp of the class described, a casing, a dating assembly comprising a U-shaped frame disposed in said casing, a plate disposed on each of the opposite sides of the transverse portion of said U-shaped frame, each of said plates having inclined slots formed therein, a block having a threaded opening therein disposed between said plates, bosses on said block engaging in the slots in said plates, and a threaded bolt journaled in said casing and threaded through the opening in said block for moving said dating assembly relatively to said casing.
9. In a stamp of the class described, a casing, a dating assembly comprising a U-shaped frame disposed in said casing, a notch formed on each of the opposite sides of the transverse portion of said frame, a plate seating in each of said notches and secured to said frame, a block disposed between and carried by said plates, and means associated with said block and said casing for moving said dating assembly relatively to said casing.
10. In a stamp of the class described, a casing, a dating assembly comprising a U-shaped frame disposed in said casing, a plate disposed on each of the opposite sides of the transverse portion of said U-shaped frame, each of said plates having a plurality of slots formed therein, means on said frame engaging in certain of said slots in said plates for securing said plates to said frame, a block disposed between said plates, bosses on said block engaging in the other slots in said plates, and means associated with said block and said casing for moving said dating assembly relatively to said casing.
11. In a stamp of the class described, a casing, a dating assembly comprising a U-shaped frame disposed in said casing, a plate disposed on each of the opposite sides of the transverse portion of said U-shaped frame, a block disposed between and carried by said plates, a bolt associated with said block and with said casing for moving said dating assembly relatively to said casing, and means carried by said bolt for preventing endwise movement of said bolt relative to said casing.
12. A stamp of the class described comprising a casing, a dating assembly disposed in said casing, printing characters carried by said dating assembly, a stamping assembly having a slot therein associated with said casing, printing characters carried by said stamping assembly, a rotatable member journaled in said casing, and means connecting said rotatable member with said dating assembly and including means movable transversely of the casing upon rotation of said member to adjust said dating assembly relatively to said slot, whereby the printing charac-
- ters carried by said dating assembly can be disposed in the plane of the printing characters carried by said stamping assembly.
13. A stamp of the class described comprising a casing, a dating assembly disposed in said casing for movement in the vertical plane thereof, a rotatable member journaled in said casing, and means connecting said rotatable member with said dating assembly and including means movable in a plane disposed in angular relation to the plane of movement of said dating assembly for moving said dating assembly relatively to said casing.
14. A stamp of the class described comprising a casing, a stamping assembly, attaching members secured to said stamping assembly, means comprising a plurality of arms secured to the inner surface of said casing, a hook formed on each of said arms and engaging said attaching members to positively lock said stamping assembly to said casing, and means carried by said arms for moving said hooks out of engagement with said attaching members to permit detachment of said stamping assembly from said casing.
15. A stamp of the class described, comprising a casing, a stamping assembly, attaching members secured to said stamping assembly, means comprising a plurality of arms each secured at one end to the inner surface of said casing, a hook formed on the other end of each of said arms and engaging said attaching members to positively hook said stamping assembly to said casing, and means carried by and disposed intermediate the ends of said arms for moving said hooks out of engagement with said attaching members to permit removal of the stamping assembly from the casing.
16. A stamp of the class described, comprising a casing, a dating assembly disposed in said casing, a screw extending transversely of said casing and rotatably journaled therein, and means connecting said dating assembly with said screw for moving said dating assembly relatively to said casing upon rotation of said screw.
17. A stamp of the class described, comprising a casing, a dating assembly disposed in said casing, a screw extending transversely of said casing and rotatably journaled therein, a threaded block mounted upon said screw, and means connecting said dating assembly with said block for moving said dating assembly relatively to said casing upon rotation of said screw.
18. A stamp of the class described, comprising a casing, a dating assembly disposed in said casing, a screw extending transversely of said casing and rotatably journaled therein, a threaded block mounted upon said screw, and a plurality of plates operatively connecting said dating assembly with said block for moving said dating assembly relatively to said casing upon rotation of said screw.
19. In a stamp of the class described, a casing, a dating assembly comprising a frame disposed in said casing, a plurality of plates disposed on said frame, a block operatively connected with said plates, and means associated with said block and said casing for moving said dating assembly relatively to said casing.
20. In a stamp of the class described, a casing, a dating assembly comprising a frame disposed in said casing, a pair of opposed plates mounted on said frame, a block disposed between and operatively connected with said plates, and means associated with said block and said casing for

moving said dating assembly relatively to said casing.

21. In a stamp of the class described, a casing, a dating assembly disposed in said casing, a rotatable member extending between and having its ends journaled in opposite side walls of said casing, and means operatively associated with said rotatable member and said dating assembly to adjust said dating assembly relative to said casing.

22. In a stamp of the class described, a casing, a dating assembly disposed in said casing for vertical movement with respect thereto, a rotatable member associated with said casing, means mounted on said rotatable member for translational movement with respect thereto, and means connecting said first named means with

said dating assembly whereby translatory movement of said first named means will cause vertical movement of said dating assembly.

23. An operating wheel of the class described comprising a disc having a plurality of openings therein, and an arcuate groove formed on one face of said disc and connecting said openings, said openings being countersunk on the side of the disc having the arcuate groove, and a hub of resilient material disposed on the opposite face of said disc, said hub having portions of the material thereof extending into said openings and groove to secure said hub to said disc and to restrain relative movement of said hub with respect to said disc.

LOUIS MELIND.
